UNITED STATES PATENT OFFICE.

SWAN TEVANDER, OF TOLEDO, OHIO, ASSIGNOR TO AMERICAN CAN COMPANY, OF NEW YORK, N. Y., A CORPORATION OF NEW JERSEY.

SCREW-CAP NOZZLE FOR CANS.

No. 923,214.

Specification of Letters Patent.

Patented June 1, 1909.

Application filed June 3, 1908. Serial No. 436,391.

To all whom it may concern:

Be it known that I, SWAN TEVANDER, a citizen of the United States, residing in Toledo, in the county of Lucas and State of Ohio, have invented a new and useful Improvement in Screw-Cap Nozzles for Cans, of which the following is a specification.

My invention relates to improvements in pouring nozzles for cans.

10 The object of my invention is to provide a screw cap pouring nozzle of a simple, efficient and durable construction, having a nozzle cap piece adapted to be soldered or otherwise secured to the can head at the cap 15 opening therein, and furnished with a valve seat and pouring lip, and in which it will not be necessary to entirely remove the screw plug from the nozzle cap piece in order to open the nozzle for pouring, and in which 20 the screw plug may be entirely removed from the nozzle cap piece for filling purposes.

My invention consists in the novel construction of parts and devices and in the novel combinations of parts and devices 25 herein shown and described by which this object or result is practically accomplished.

In the accompanying drawing forming a part of this specification, Figure 1 is a plan view of a screw cap pouring nozzle can embodying my invention. Figs. 2 and 3 are detail sections on lines 2-2 and 3-3 respectively of Fig. 1. Fig. 4 is a detail plan view of the nozzle with the screw plug removed.

35 In the drawing, 1 represents a can having its upper head 2 furnished with a cap opening 3 and cap seat 4 surrounding said opening.

5 is the cap piece or shell of the nozzle having an integral annular flange 6 soldered or 40 otherwise secured to the cap seat 4 of the top head 2 of the can surrounding the opening therein. The annular flange 6 is also furnished with an annular valve seat 7. The nozzle cap or shell 5 is further furnished with 45 an integral pouring lip 8 and with a marginal rim or flange 9 at its upper edge. The nozzle cap or shell 5 carries at its upper part a screw sleeve 10 having a rim or flange 11 at its upper end which is clenched or folded 50 over the flange or rim 9 of the nozzle cap or shell 5 at its extreme outer edge 12. The flange 11 of the screw shell 10 extends across or bridges the pouring lip 8 of the nozzle cap 5. The nozzle cap 5 and screw sleeve 10 are 55 thus rigidly and firmly secured together so

that one reinforces and braces the other. The screw sleeve 10 fits inside the nozzle cap 5 and is materially shorter in length than the same so as to leave an ample opening at the pouring lip under the lower end of the screw sleeve 10. The screw plug 13 is furnished with screw threads 14 engaging the screw threads 15 of the screw sleeve 10, and it is provided with a leather or other elastic packing 16 at its lower end, preferably secured 60 thereto by a rivet 17 and washer 18. The screw plug 13 is preferably of sheet metal, the same as the other parts of the nozzle, and it is furnished with an enlarged rim or handle 19 having knurls 20 and closed by a top 70 21 which is embraced by the flange 22 of the screw plug at the upper end of the screw plug 13. The pouring lip or spout portion 8 of the nozzle cap 5 is preferably furnished with a hinged dust guard or cover 23 connected to 75 the rim or flange 11 of the screw sleeve 10.

I claim:

1. A screw cap pouring nozzle comprising in combination a nozzle cap adapted to be secured to the can head, and provided with an integral pouring lip and a valve seat at its lower end, a screw sleeve fitting within the nozzle cap and having a flange at its upper end secured to the upper end of the nozzle cap, said flange on said screw sleeve 80 extending across said pouring lip and a screw plug fitting within the screw sleeve at the upper end of the nozzle cap and engaging at its lower end the valve seat at the lower end of the nozzle cap, substantially as 90 specified.

2. The combination with a nozzle piece having an integral pouring lip and valve seat and a projecting rim at its upper end, of a screw sleeve having a flange at its upper 95 end interfolded with the rim of the nozzle piece, and at its front portion bridging said pouring lip and a screw plug, substantially as specified.

3. The combination with a nozzle piece 100 having an integral pouring lip and valve seat and a projecting rim at its upper end, of a screw sleeve having a flange at its upper end interfolded with the rim of the nozzle piece, and at its front portion bridging said pouring 105 lip and a screw plug, said screw plug having an elastic packing at its lower end, substantially as specified.

4. The combination with a nozzle piece having an integral pouring lip and an annu 110

lar flange at its lower end adapted to be soldered to a can head and forming a valve seat and provided at its upper end with a projecting rim, of a screw shell fitting with-
5 in said nozzle piece and having a marginal flange folded over the rim of the nozzle piece and bridging the pouring lip thereof, a cover for said pouring lip hinged to the front por-
tion of said marginal flange and a screw plug

peripherally engaging said screw shell, and 10 engaging at its end the valve seat so that the nozzle may be opened for pouring without removing the plug, substantially as speci-
fied.

SWAN TEVANDER.
